1

This invention relates to forming paper clips of the conventional wire type having two looped ends at one end thereof and one at the opposite end thereof and two parallel straight runs at each side thereof including portions connecting the loops, the principal object being the provision of a method, and apparatus for carrying out the same, by means of which paper clips of the type described may be quickly, readily and economically manufactured.

Objects of the invention include the provision of a method of forming paper clips of the type described comprising the steps of moving a length of wire stock in a direction perpendicular to the length thereof continuously in one direction and bending the said wire through approximately 180° at consecutively different points in the length thereof to form a completed clip; the provision of a method as above described including the step of backing up the length of wire against retrograde movement at the points of consecutive bending in the length thereof and eliminating the backing up effect at each point immediately upon the bending there effected; and the provision of a method as above described in which the wire is rigidly held at one end thereof for the bending operations, the bending operations are initiated adjacent that end of the wire most remote from said rigidly held end, and the points of bending occur in consecutively closer relation to said rigidly held end.

Further objects of the invention include the provision of apparatus of the type described including means for relatively moving a straight length of wire continuously in one direction with respect to a cooperating part, and members positioned to strike and form the wire consecutively at different points thereon during said relative movement; the provision of apparatus for fabricating wire into paper clips at high speed by providing a plurality of wire feeding stations within the length of a member continuously moving in the same direction; the provision of apparatus of the type described including reciprocable wire engaging means movable into and out of engagement with the wire during the forming operation; the provision of apparatus of the type described including means for continuously feeding wire into the apparatus, forming the wire into clips, depositing the clips into boxes and then removing the boxes; the provision of apparatus of the type described including a rotatable carriage on which a length of wire is adapted to be deposited and formed in the manner stated; the provision of apparatus of the type described in

which the carriage is provided with abutments adapted to back up the wire in its movement with the carriage and stationary forming means adapted to consecutively engage the said wire at different points in the length thereof during rotation thereof on said carriage; the provision of apparatus of the type described in which the abutments are carried by plungers reciprocable into and out of operative position during rotation of said carriage and bodily movable with said carriage; the provision of apparatus of the type described in which the forming means each comprise a striker member and a die member carried by the stationary part of the apparatus; the provision of apparatus of the type described in which the forming mechanism is made up in units applicable to and removable from the apparatus as such and each including a striker member and a rotatable die member; the provision of apparatus of the type described including means for continuously feeding wire to the forming portion of the machine and severing said wire at predetermined points in the length thereof to provide a length of stock for formation into a clip; and the provision of apparatus of the type described including a plurality of wire feeding and wire forming mechanisms each cooperable to form lengths of such wire into paper clips, and a common hopper means arranged to receive the clips from all of the forming means and to deliver the same to a common packaging portion on the machine.

Further objects and advantages of my invention will be apparent from the description which follows when considered in connection with the accompanying drawings in which like numerals indicate like parts wherever shown and wherein:

Figure 1 is a partially broken plan view of a machine for fabricating wire embodying the present invention;

Fig. 2 is a side elevational view of the machine of Fig. 1, looking in the direction of the arrow 2 as indicated in Fig. 1, with one of the wire-supporting brackets omitted;

Fig. 3 is a vertical sectional view taken on the line 3—3 of Fig. 1 to illustrate the main driving means of the machine of the present invention and a typical wire feeding station with the tumbling mechanism thereat partly sectioned to more clearly show the means for straightening the wire as the same is fed to the machine;

Fig. 20 is a fragmentary plan view taken on the line 20—20 of Fig. 19, showing the pawl and ratchet illustrated in Fig. 19;

Fig. 21 is a horizontal sectional view taken on line 21—21 of Fig. 19 to more clearly illustrate the cross-sectional configuration of a typical die member and strike member;

Fig. 22, 23, and 24 are fragmentary, more-or-less diagrammatic plan views to show the stages of operation in the second forming operation;

Fig. 25 is an enlarged, fragmentary, vertical sectional view taken on line 25—25 of Fig. 24, showing the second plunger in inoperative position after the second forming operation;

Figs. 26, 27 and 28 are fragmentary, more-or-less diagrammatic plan views showing the final forming operation;

Fig. 29 is a fragmentary vertical sectional view taken on line 29—29 of Fig. 28 to show the posi-

tion of the innermost plunger immediately at the termination of the forming operation and before the plunger is withdrawn to inoperative position;

Fig. 30 is a greatly enlarged, fragmentary, vertical sectional view taken on line 30—30 of Fig. 28 and showing the third plunger in inoperative position after the final forming operation;

Fig. 31 is a plan view of a finished paper clip made by the machine shown in the preceding views.

Fig. 32 is a fragmentary plan view taken on a line corresponding to that on which Fig. 10 is taken, but only of that portion of the mechanism corresponding with that shown in the left hand part of Fig. 10, showing a modified form of construction;

Fig. 33 is a fragmentary sectional view taken on the line 33—33 of Fig. 32;

Fig. 34 is a fragmentary sectional view taken on the line 34—34 of Fig. 32; and

Fig. 35 is a fragmentary sectional view taken on the line 35—35 of Fig. 34.

The basic feature of the present invention resides in a method of forming paper clips of the character described by continuously relatively moving, with respect to cooperating parts, a length of wire stock in one direction approximately perpendicular to the length of the wire stock and bending said stock at consecutively different points in the length thereof during said continuous relative movement in one direction, to form a completed clip. In such bending it contemplates backing up the length of wire stock against retrograde movement at the points of bending and removing such backing up effect at each point as the bending at such point is completed. In apparatus for carrying out of such method the backing up of the wire is preferably carried out by abutment members arranged in backing up relation with respect to the wire at each point of bending, which abutment members are withdrawable at each point of bending as the bending at such point is completed. For the purpose of effecting the bending of the wire at each of such abutments the apparatus contemplates the use of forming means movable relative with respect to said abutments whereby to cooperate therewith to effect bending of the wire about said abutments. Such apparatus preferably includes means for clampingly holding one end of the wire stock in fixed position with respect to its supporting member until the completion of the bending operation and then releasing the clamping effect to free the clip for discharge from the machine.

In the broader aspects of the invention it will be appreciated that whether the wire and the abutment means are stationary and the forming means moved, or whether the forming means are stationary and the wire and the abutment means move relative thereto, is more or less immaterial, the latter form of construction being generally preferred for mechanical reasons and therefore being incorporated in the embodiment of the present invention shown in the drawings by way of illustration.

It will be further appreciated that whether the movable part of the machine, whether it be that part which carries the wire stock and the abutments or whether it be that part of the machine which carries the forming means, moves in a straight or circular path, is more or less immaterial. Here again, however, it is preferable for mechanical reasons that the two main rela-

tively movable parts of the machine be rotatable with respect to each other and, accordingly, it is this form of apparatus that is illustrated in the drawings by way of illustration.

In the embodiment of the machine of the present invention shown in the accompanying drawings by way of illustration, a base is provided to support the machine on a floor or other suitable supporting surface. The upper portion of the base, which is hollow, provides for housing certain of the mechanism interiorly thereof, and at the top thereof there is provided a head plate around which are positioned a plurality of wire feeding means, each of which feeds a length of wire into a corresponding groove in the head plate. Thereafter, the inner end of the wire is moved downwardly and clamped to a rotating carrier, after which reciprocable wire-engaging means contact the wire remaining in the head slot, moving the same downwardly onto the rotating carriage. At or about the same instant, a cutter in the periphery of the carriage severs the wire thus held on the carriage and the severed length of wire is carried along to the forming means.

The forming means include strikers and rotatable dies depending from the lower surface of the head plate in consecutive sets, and fashion the wire into a clip as it successively engages the forming members. As each set of forming means is passed, one of the wire-engaging means retires to inoperative position, and when the clip is completed, it is thrown by centrifugal force into a hopper. From the hopper, the clips are delivered to cartons held by a carton carrier, which moves in timed relation with the wire feeding means and rotating carrier, to move an empty carton into place as soon as the preceding one is filled.

As will hereinafter become more clear, one or any greater number of wire feeding stations may be affixed to the periphery of the head plate, the limit of stations being determined solely by the size of the head plate and the size of the feeding stations, and in the present case there are shown three wire feeding stations by way of illustration and not by way of limitation.

Referring to Figs. 1 and 2, a paper clip fabricating machine 10 is illustrated as having a base which includes the legs 12 and an upper hollow housing portion 14 bolted to the legs 12. By means of the legs 12, the apparatus may be supported on a floor of a shop, or on any other suitable supporting surface. The housing portion 14 contains certain of the apparatus interiorly thereof and, as may be seen most clearly in Fig. 3, a stationary head plate 16 is mounted in spaced relation to and above the top of the housing portion 14 by means of a plurality of spacer bars 18 on which is formed an enlarged portion 20 adapted to rest upon the adjacent upper surface of the housing portion 14 and support the head plate 16. The spacer bars 18 are rigidly fixed to the housing portion 14 and to the head plate 16 by means of bolts 22 which are threaded into the lower ends of the spacer bars and bear upon the washers 24 when the bolts are turned tight.

A plurality of wire feeding stations, generally indicated as 26, are positioned about the periphery of the head plate 16. In the present case, as stated in the foregoing, three wire feeding stations are shown by way of illustration and these are positioned about the head plate 16 in equally angularly spaced relation with respect to each other, and the wire cut-off point of each station,

as hereinafter will become more clear, is concentrically positioned with respect to the center 28 of the head plate 16 which is on the vertical axis of the machine. For purposes of simplifying design and positioning of the feeding stations 26 on the machine of the present invention, the head plate 16 is here shown as being annular in plan view. Obviously, any plan form may be provided for the head plate 16, depending upon the number of wire feeding stations to be mounted on such apparatus; the annular form providing for more readily positioning the same thereabout.

At each of the wire feeding stations, means are provided for supporting a reel or roll of wire 30. In the present case, each roll of wire 30 is supported by means of a bracket 32 which is attached to the housing 14 and provides the outwardly directed arms 34 on opposed sides thereof between which a spindle 36 extends to rotatably support the roll of wire 30.

Inasmuch as each of the wire feeding means is identical, only one is hereinafter described. Thus, at each of the wire feeding stations 26, a pair of housings 38 and 40 (Fig. 1), radially spaced from one another with respect to the axis of the machine, are provided. The housings 38 and 40 are hollow interiorly and serve to cover driving mechanism, later to be explained, for driving wire feeding rollers.

As may be seen best in Fig. 4, the housing 38 provides a bearing supporting portion 42, substantially perpendicular to one face thereof, in which a shaft 44 is journaled for rotation upon bearings 46 and 48 positioned in portion 42 at opposite ends of said shaft. In a similar manner, the housing 40 journals a shaft 50 (see Fig. 3) for rotation in an outwardly directed projection 52 of that housing. On the outer ends of each of the shafts 44 and 50, respectively, as best shown in Fig. 3, a wire feeding roller 54 is fixed. The wire feeding rollers are peripherally grooved at 56 and the wire 30 is forcibly held in each thereof by a pressure roller 58. Each roller 58 is mounted directly above its corresponding feed roller 54 and each is peripherally grooved as at 60, in complementary relation to the peripheral section of the corresponding feed roller for reception of the periphery of the latter therein. The pressure rollers 60 may be adjusted to vary the pressure on the wire 30 holding it in the groove 56.

To mount the rollers 58, and as best shown in Fig. 4, a shaft 62 is positioned in overlying, substantially parallel relationship to shaft 44. The shaft 62 is journaled for rotation in bearings 64 and 66 carried by a housing 67 which in turn is supported for arcuate adjustment by means of a radially extending arm 68 (Fig. 1) about a horizontally directed post 70 midway between the axes of rotation of shafts 44 and 50. In like manner, a shaft 72 (Fig. 3), positioned in overlying, substantially parallel relationship to shaft 50 is journaled for rotation within a housing 74 having a radially extending arm 76 (Fig. 1) to support the same for arcuate adjustment about the post 70. Thus, the grooves 56 provide for positively holding the wire 30 in position between the pressure rollers 58 and the feed rollers 54 and 50 are rotated by the driving mechanism of the apparatus.

The pressure of the feeding rollers 58 may be varied by means of nuts 80 (Fig. 4) which are adjacent the housings 67 and 74, respectively. The nuts 80 are threaded onto upwardly directed bolts 82 which pass through openings provided

therefor in arms 68 and 76 adjacent the housings 67 and 14 and press upon a washer 84 mounted upon a spring 86 which encircles the bolts 82. By turning the nuts 80, the pressure of the rollers 58 on the wire 30 may be varied. After adjusting the pressure of the rollers 58 in this manner, the adjustment nut 80 is locked in the adjusted position by means of a lock nut 87.

To straighten the wire as the same is fed, a wire straightener is positioned between the rollers just described. Considering the broader aspects of the present invention, the wire straightening means may be of any type so long as it provides for delivering straight wire for feeding into the head plate 16. In the case shown, and as best brought out in Fig. 3, the wire straightener comprises a tumbler 88 journaled for rotation upon shafts 90 and 92 thereof in bearings 94, 96, and 98 provided in a bearing support 100 and a housing 102. The tumbler 88 is rotated in timed relation to the rotation of the wire feeding rollers 54 and has adjustable wire straightening means in the form of radially directed plungers 104 which are positioned in sets of three at opposite ends of the tumbler 88 so that the rollers 106 journaled on the inner ends thereof engage the wire 30. In each set of plungers 104, one of the rollers 106 is spaced intermediate the other two rollers 106 and presses in an opposite direction so that a stress reversal occurs in the fibers of the wire to accomplish straightening of the same in a conventional manner.

The plungers 104 are provided at their outer ends with a shank 108 adapted to extend slightly through the periphery of the tumbler 88 and have a nut 110 threaded thereon for holding the plungers in position. As was stated previously, the plungers are arranged in sets of three at opposite ends of the tumbler 88, and as may be seen in Fig. 3, the sets are positioned so that one set lies in a plane substantially perpendicular to the plane of the set at the other end of the tumbler. Thus, as the wire is fed by the first set of wire feeding rollers it passes through the tumbler 88 where it is engaged by the two sets of plungers which effect straightening of the wire before the same passes into and through the second set of feeding and pressure rollers, resulting in a straight length of wire being fed into the head plate 16. Preferably, as indicated in Figs. 1 and 3, the wire 30 after being withdrawn from the rolls and before it is introduced into the straightening apparatus above described, is passed through a die structure, indicated generally at 112, suitably fixed with respect to the stationary part of the machine. The die structure 112, which is somewhat similar to a wire drawing die, serves to eliminate the greater part of the curl of the wire, resulting from being wound in a roll, before the wire enters the final straightening operation.

The feeding apparatus described in the foregoing feeds the wire 30 through a die 116 into a groove 118 in the lower surface of the plate 16 as best brought out in Figs. 9 and 10. As indicated in Fig. 7 the groove 118 is approximately radial of the axis of the rotatable carriage, but is somewhat offset from a true radial position as shown. The die 116 is retained within a die block 128 fixed to the periphery of the head plate 16 and an opening 121 (Fig. 10) in the die 116 is positioned to be in line with the groove 118 formed in the lower surface of the head plate 16. Thus, the wire 30 is guided by

the die 116 into the groove 118 as it moves into such groove.

To provide for severing the wire after it is fed into full depth of the slot 118 and thereafter fashioning it into a paper clip, a rotatable carriage or head 122 is mounted below the head plate 16 and spaced slightly therefrom for rotation relative thereto.

As may be seen best in Fig. 6, the rotatable carriage or head 122 is keyed at 124 to a shaft 126 journaled for rotation in bearings 128, 130, and 132 housed in the head plate 16 and the housing 14 on the axis of the machine. A nut 134, threaded on the upper end of the shaft 126, is turned tightly against the upper surface of the carriage or head 122 to hold a shoulder portion 136 formed on the lower surface of the carriage 122 into abutting relationship with a collar 138 on the shaft 126 which in turn bears upon the bearing 130. Near the lower end of the shaft 126, an integral flange 140 is formed thereon and a pair of bevel gears 142 and 143 are positioned one above the other on the shaft 126 in abutting relationship with the flange 140. The gears 142 and 143 are held in spaced relationship with respect to the bearing 130 by means of a shouldered collar 144 which carries the inner race of the bearing 130 and when the nut 134 is tightened, the carriage 122 is held against axial movement. As will be observed in Fig. 6, the gear 143 is a composite gear comprising a hub and a ring bolted thereto. The gear 143, as will later be described, engages driving means to accomplish rotation of carriage 122.

When the wire is fully fed into the groove 118 in the head plate 16, means are provided to move the same into position on the carriage 122 and clampingly hold the same thereon. For this purpose, and as brought out in Fig. 6, in-line plungers 148, 150 and 152, arranged with their axes in a plane approximately including the axis of the shaft 126, are mounted in the rotatable carriage 122 in parallel relation to the axis of the shaft 126. As indicated in Figs. 22, 23, and 24, these plungers are of rectangular cross-sectional configuration. On the lower ends of the plungers, rollers 154, 156, and 158, respectively, are rotatably mounted and are in cooperative engagement with the surfaces of cam tracks 160, 162, and 164, respectively. The cam tracks are annular in form, concentric with the axis of the shaft 126, and the upper surface of each has rises and valleys, and the plungers move to and from operative position as the rollers thereof follow the cam tracks in rotating with the carriage 122.

Thus, after the wire 30 is fed into full depth in the slot 118, rotation of the carriage 122 brings a holding member 170 (Figs. 6, 25 and 30) into engagement with the inner end of the wire. The holding member 170 is mounted on the carriage 122 adjacent to the innermost plunger 152 to travel in a circular path in a groove 172 formed in the head plate 16. An end of the holding member 170 extends in overlying relationship to a portion of the plunger 152 and in the lower surface of such end a slot 171 is milled. As will hereinafter become clear, the dimensions of the slot 171 are such that in the final forming operation, which completes the fashioning of a paper clip, clearance is provided to accomplish bending of the wire at that time without interference between the same and the walls defining said slot 171 and thereafter upon release of the

finished clip, by retraction of the plunger 152, allowing said clip to be freely thrown from the slot by centrifugal force.

To accomplish holding of the innermost end of the wire 30 by the holding element 170, the overlying end of the member 170, as may be seen in Fig. 29, is provided with a rearwardly sloping leading end 174. It is this leading end 174 which initially engages the innermost end of the wire when the same is fully in the groove 118 in the head plate 16. Such innermost end of the wire is not lying in the groove 118 but is projected beyond the inner end thereof into the circular groove 172 in the head plate 16 in which the holding member 170 rotates, and is therefore in a position to be engaged and moved downwardly by the leading edge 174 of the holding member 170. Then, as rotation of the carriage 122 continues, the innermost end of the wire is caused to travel downwardly along the surface of the leading edge 174 on the holding member 170 until it enters a groove 175, extending radially of the axis of the shaft 126, in the upper surface of the plunger 152 (see Figs. 25 and 29). The groove 175 is provided by milling the upper end of the plunger 152 to provide stepped horizontal surfaces 176 and 177, the latter of which is flush with the upper surface of the carriage 122 when the plunger 152 is in raised position. The surfaces 176 and 177 are separated by an upwardly directed shoulder, extending transversely of the direction of rotation of the carriage 122. A blade-like abutment member 178 is fixed in the upper end of the plunger 152 with the plane of its thickness vertical and parallel to and spaced from the above mentioned shoulder. The spacing of such shoulder and the abutment 178 is equal to the diameter of the wire 30 as shown in Fig. 29. The opposed lower face of the holding member 170 where it engages the wire 30 in the groove 175 is recessed for complementary engagement with the wire 30, as shown in Fig. 29, to more securely hold the wire 30 in such position. The bottom of the groove 176, thus formed, is actually a part of the surface 177 and therefore lies in the plane of the upper surface of the carriage 122, when the plunger is in its uppermost position.

At the time the innermost end of the wire 30 enters the groove 175 in the plunger 152, plungers 148, 150, and 152 are raised to uppermost position by the rotation of the carriage 122 and the co-operating cam tracks. As may be seen in Fig. 29 (sheet 11), the innermost end of the wire is then disposed in groove 175 at the level of the upper surface of the carriage 122 and there clampingly held against the lower face of the holding member 170 by the plunger 152.

Obviously, if the plunger 152 is to accomplish clamping of the wire 30, provision must be made for handling wire that is either slightly undersized or oversized. For this reason, the plunger 152, as brought out in Figs. 25 and 30, consists of upper member 152a and a lower member 152b bolted thereto and spaced therefrom for slidable movement toward and away from the upper member to compensate for variations in wire size. In the broader aspects of the invention, any means may be employed tending to maintain the spaced relation of members 152a and 152b so long as that means provides for rapid adjustment and allows the plunger to positively engage the wire.

In the present case, a block of rubber 179, shown in Fig. 25, is inserted between the members

and serves to resiliently and constantly urge the members apart while allowing the plunger 152 to clampingly hold the wire 30 with sufficient rigidity for the forming operations to be performed thereon.

At the same time that the plunger 152 is raised to clamp the inner end of the wire 30 against the stop member 170, wire engaging means or abutments 180, 181 and 182, formed on the upper ends of the plungers 148, 150 and 152, respectively, turn into engagement with the wire along with the wire cutting portion of the apparatus, and the latter acts to sever the wire 30 at the periphery of the carrier 122. The wire cutting portion of the apparatus comprises as many units as there are wire feeding stations, and these units are equally angularly spaced about the periphery of and are carried by the carrier 122.

Each wire cutting unit comprises, as best shown in Figures 10 and 13 (Sheet No. 8), a mounting member 183 removably secured in a complementary recess in the periphery of the carrier 122 by screws 184 and having an outer face flush with and forming a continuation of the peripheral surface of the carrier 122. Midway between its ends the mounting member 183 is provided with an upwardly and rearwardly inclined recess 185, the rear edge of which is inwardly and rearwardly beveled or inclined and the bottom or inner wall of which is stepped. A cutter member 186 of dove-tail cross section is received in the shallow rear portion of the recess 185 in complementary engagement with the beveled surface thereof and is releasably secured therein by a clamping and wedge block 187 removably secured in the deeper portion of the recess 185 by screws 188. The cutter member 186 is provided at its upper end with a cutting end or point 189 which projects above the upper face of the carrier 122, the lower outer marginal edge of the head plate 16 being relieved as at 190 to provide clearance therefor. The point 189 is of a shearing type rather than a knife blade type and therefore has an appreciable thickness. Accordingly, inasmuch as the inward feed of the inner end of the wire 30 stops as soon as it is severed by the point 189, means must be provided for its outer end to move out of the way of the point 189 as the latter rotates past it. This is accomplished by beveling the point 189 rearwardly and providing a notch 191 (Fig. 13) in line with each groove 118 at the radially outer end of the latter. Each notch 191 provides clearance for passage of the radially outer end of the wire 30 over the point 189 where it is pushed, after severance, due to the angle of the point 189. An arm 192 fixed to each member 183 is provided with an end which projects below the cutter member 186 and threadably receives a screw 193 arranged with its axis parallel to the direction of movement of the cutter member 186 and which abuts the lower end of the cutter member 186. The screw 193 provides for adjustment of the cutter member 186 when the screws 188 are loosened. It also serves as an abutment to limit downward movement of the cutter member 186 during operation. It will be appreciated that each unit including the mounting member 183, the cutter member 186, the clamping and wedge block 187, arm 192 and screw 193 form a unitary assemblage applicable to and removable from the carrier 122 as such. The cutting point 189 of the cutter member 186 is arranged with its cutting edge flush with the periphery of the carrier 122 and in a position 75 to substantially rub the inner face of the die 116

as the carrier 122 rotates relative to the latter, and during rotation past the die severs that portion 30a of the wire 30 which has been projected inwardly from the coil beyond the die 116 so that such severed portion of the wire may thereafter travel around with the carrier 122. The plunger 152 acts to clamp the inner end of the wire 30 to the holding member 170 at substantially the same instant that the point 189 severs the wire and therefore causes the severed end of the wire to thereafter turn with the carrier 122. The radially outer end of the severed portion 30a of the wire is still lying in the groove 118 when the last-mentioned rotation is initiated and must, of course, be brought out of the groove 118 to enable it to travel around with the carrier 122. This is accomplished by beveling the forward wall of the groove 118, as illustrated at 194 in Fig. 9, so that the projections or abutments 181 and 182 on the plungers 148 and 150, in engaging the outer end of the wire 30a, cause it to ride down the inclined wall 194 to just below the lower face of the head 16 where it is free to rotate with the carrier 122. The abutments 181 and 182 effect such result because they travel, when such plungers are in upwardly projected position, in complementary grooves 195 and 196 (see Fig. 17) formed in the lower face of the head plate 16, and which grooves extend above the upper limits of the groove 118. The outer end of the wire 30a in riding down the wall 194 is in contact with the forward faces of the abutments 181 and 182, and the corresponding plungers 148 and 150 are provided with transverse grooves 197 and 198, respectively, extending in the direction of the length of the wire 30a immediately in advance of such abutments (see Figs. 11 and 12, Sheet No. 7), in which the corresponding portions of the wire 30a are received and held at the same level as the inner end thereof is held by the plunger 152. Only the groove 197 in the plunger 148 is shown in Figs. 11 and 12, but both are indicated by dotted lines in Fig. 17. Thereafter, continued rotation of the carriage or carrier 122 delivers the wire 30a to forming units to accomplish fashioning of the wire into a clip.

In Fig. 7, it may be seen that in the vicinity of each of the wire feeding stations 26, and grooves 118, a series of wire forming units are located as indicated by the numerals 199, 209, and 204. Each of the forming units is removably positioned in the head plate 16 and provides means depending from the lower surface of the head plate 16 for fashioning the wire into a paper clip as the same is brought into engagement therewith by means of the rotating carriage 122.

Inasmuch as each of the forming units is substantially identical, only one is described, and in Fig. 18 the unit 199 is shown wherein a striker member 202 and a die 203 are shown in that unit in depending relationship to the lower surface of the head plate 16. The striker member 202 and the die 203 are mounted in an annular, cylindrical housing 204 fitting in an opening 205 provided therefor in the head 16 with its axis parallel to the axis of the shaft 126. The housing 204 is retained therein by a shoulder portion or flange 206 which engages the upper surface of the plate 16, and the bottom of the housing then lies in the plane of the lower surface of plate 16. As may be seen, the striker member 202 extends through an opening provided therefor in the housing 204 in such a manner that the lower end of the striker member extends below the lower surface of the plate 16 and is positively held

therein by a bearing 208 in which the shaft 210 extending upwardly from the die 203 is journaled for rotation. The lower surface of the die 203 lies in the same horizontal plane as the lower surface on the striker member 202 and is retained in such a position by a nut 212 threaded on the upper end of the shaft 210. When the nut 212 is turned tightly down against an abutting surface of a hollow collar or hub 214 of a toothed wheel 216 surrounding and keyed to the shaft 210 above the bearing 208, the hub 214 is brought tightly against the upper surface of the bearing 208. The bearing 208 is fitted in an opening 218 provided in the housing 204 and with its lower surface resting on a shoulder portion 220 at the bottom of the opening 218 and on the top of the head of the striker member 202, thus holding the latter in position. An annular washer 222 abuts the top of the bearing 208 and holds the same in position when bolts 224, projecting through a cover 226 and threading into the head 16, are tightened to hold the cover 226 in place. As will later be described, the toothed wheel 216 provides for intermittent rotation of the die 203 during the forming operation.

Thus, after the portion of wire 30a is cut from wire 30 and is moved into the grooves in the plungers, the radially outer end thereof is first brought by the carriage 122 into engagement with the striker 202, as seen in Fig. 14, causing the end of the wire to bend in a direction away from the direction of rotation of the carriage 122. Next, as brought out in Fig. 15, the bent end of the wire 30a, while still bent around the member 180, is brought into engagement with the die 203. It will be observed that the die 203 is provided with a plurality of substantially semicircular, equally angularly spaced flutes 230 and the bent end of the wire is brought into one of the flutes 230. The flutes 230 are of such size and shape, in conjunction with the striker 202, as to effect a combined bending and coining action on the bent end of the wire. Such action fashions the bent end of wire 30a into a U-shaped hook, as illustrated in Fig. 15.

Now, considering the cross-sectional configuration of the wire-engaging or abutment member 180 on the upper surface of the plunger 148, as brought out in Figs. 14, 15, and 16, it may be observed that member 180 has one side which tapers inwardly with respect to a line radial to the shaft 126 and passing through its center. As the curved end of the wire passes through the die 203, the trailing edge of the cooperating flute 230 comes into contact with the turned end of the wire, bending it toward the main portion of the wire, slightly diminishing the spacing of the open end of the U to allow for spring back of the wire after the forming operation so that the two legs of the U will be parallel to each other.

Up to this time, the wire-engaging means 180 is still in engagement with the wire 30a. However, at or about the same instant the looped end of the wire leaves the die 203, the plunger 148 moves to inoperative position, illustrated in Fig. 17, due to the co-operation between cam track 160 and springs 232. As may be seen in Fig. 11 (Sheet No. 7), the springs 232 are positioned in aligned openings in the rotatable carriage 122 and the lower body of the plunger 148, and forcibly urge the roller 154 of that plunger toward cam track 160. At this phase in the rotative movement of carriage 122 the roller 154 has come into engagement with a valley in the cam

track 160 and the plunger is moved into inoperative position.

Should the springs 232 fail to operate to return the plunger 148 to inoperative position, means (Fig. 17) in the form of a roller 234 which rotatably engages a cam 236 provide for returning the plunger 148 to inoperative position. The roller 234 is mounted on one outer end of a pin 240 which supports the roller 154 in the plunger 148, and the roller 234 moves into operative engagement with a downwardly facing cam surface 238 on the cam member 236 to positively move the plunger 148 into retracted position.

When the plunger 148 is moved to inoperative position during rotation of the carriage 122, as above described, the wire engaging means 180 is, of course, retracted, leaving the formed end of the wire free, and only the plungers 150 and 152 remain in engagement with the wire 30a to clamp it to the carriage 122.

The partially formed wire 30a is then carried on to the forming unit 200 where its radially outer end portion, which includes the first bent portion, contacts the striker member 246 of that station, as shown in Fig. 22, and is again bent away from the direction of rotation to a position substantially perpendicular to the radially disposed unformed portion of the wire as shown. Then, as brought out in Fig. 23, it is forcibly brought into engagement with a die member 248, similar to the die member 203 first described, where it enters one of the flutes 250 thereof, causing the wire to be bent in the form of a closed oval as shown. The flutes 250 of the die 248 are like the flutes of the die 203; that is to say, substantially semicircular in form, but are slightly larger to accommodate the increased size due to the doubling of the wire. It will be observed that the cross-sectional configuration of the wire-engaging means 181 on the plunger 150 is U-shaped and the length thereof is sufficient to clear the end of the doubled wire when the same is folded closed as illustrated in Figs. 23 and 24. When the partially formed wire 30a leaves the die member 248, one of the flute edges contacts the folded wire to firmly press the previously bent end against the main body of the wire and prevents the wires from separating after leaving the die.

At this time, the plunger 150 is retracted by means of springs (not shown) of the same general construction and arrangement as the springs 232 for the plunger 148. In the event of failure of the springs, retraction of plunger 150 is brought about, as best shown in Figs. 17 and 25, by a roller 252 and a cam 254 having a surface 256 along which the roller 252 may roll. The roller 252 is mounted on one end of a pin 258 which provides for mounting the roller 156 in the plunger 150. Movement of the plunger 150 into inoperative position removes the wire-engaging member 181 from between the bent partially formed wire 30a, which then continues on to the next forming unit.

At forming station 201, shown in Figs. 26, 27, and 28, the partially formed wire 30b first engages a striker member 260 where it is again bent rearwardly or opposite to the direction of rotation, about the abutment 182, to a position substantially perpendicular to the portion of the wire still held by the plunger 152 against the holding member 170, as brought out in Fig. 26. Thereafter, as brought out in Fig. 27, it is forcibly delivered to a die member 262, similar to the die members 203 and 248 above described,

having the fluted openings 264 therein. As the partially formed wire enters one of the fluted openings in the die member 262, it is given another U-bend, this time around the blade 178 which still aids in holding the wire in operative position, to complete forming of a clip 30b. This is illustrated in Figs. 27 and 28, and thereafter the plunger 152 moves to inoperative position withdrawing the blade 178 and the wire-engaging means 182 with it, freeing the finished clip 30b.

The plunger 152, similar to the plungers 148 and 150 is urged to an inoperative position by springs (not shown) or, in the event of failure of the springs, by means of a roller 265 which operatively engages a cammed surface 266 on cam 268, as brought out in Fig. 25.

Bearing in mind the operation of the rotatable dies, as described in the foregoing, it will be appreciated that means must be provided to prevent rotation of any die in excess of that required to position a flute therein for a succeeding formation operation. Any means may be used to accomplish this purpose, so long as it allows for bringing a flute of the die into co-operative alignment with the bent end of wire after it leaves a striker member so that the same may be fastened in the die. In the present case, a detent mechanism is used.

Thus, in Figs. 19 and 20, a plunger 270 is shown slidably positioned in an opening 272 in the cover 222 of the forming unit 199. The outer end of the opening 272 is closed by means of a plug 274, which is held in position by a pin 276. Between the plug 274 and the plunger 270, resilient means in the form of a spring 278 is placed to urge the plunger 270 toward the toothed wheel 216 fixed to shaft 210 of die 203. A wheel 280 is rotatably mounted by means of a pin 282 at the outer end of the plunger 270 and enters an interdental space between the teeth on wheel 216 to rollingly engage the flanks of adjacent teeth. The wheel 216 is provided with the same number of equally angularly spaced teeth as there are flutes 230 in the die 203, namely four in the construction shown, as seen in Fig. 20. The wheel 216 is fixed on shaft 210 in such a manner that the flutes 230 in die 203 therebelow may be brought into meshing relationship with the bent end of the wire 30a and the co-operating member 180, as the carriage 122 rotates, and maintained in such position by allowing rotation of die 203 to the extent of one flute space. The teeth of the wheel 216 are so proportioned that the wheel 280 may roll from one to a succeeding interdental space thereof and position the die 203 to properly receive the next bent wire and co-operating member 180. Therefore, as die 203 is rotated by the wire 30a and member 180, the roller 280 rolls from one to the succeeding interdental tooth space and there yieldingly resists further rotation of the wheel 216 and die 203. The dies of all three wire forming units 199, 200, and 201 are all similarly controlled.

As stated in the foregoing, when a clip 30b is fully formed the same is free of all the plungers in the rotatable carriage 122. Thereafter, due to centrifugal force, occasioned by rotation of the carriage 122, the clip 30b is thrown into a chute 290 (see Fig. 6). Three of the chutes 290 are provided, one at each forming station, and each delivers the clips thrown therein to a hopper 292. The hopper 292 has sloping sides which taper toward the center thereof and is open at its lower end for discharging the clips

into cartons or boxes held therebelow on a carrier.

In the present case and as brought out in Figs. 2 and 5, a carrier 294 is rotatably mounted, by means of shaft 296, below the housing 14 of the base in off-center relation to head 16 and carriage 122. The shaft 296, as shown in Fig. 5, is journaled for rotation in a bearing 298 and a bearing 300 spaced from the bearing 298 by a collar 302, all of which is retained in a boss on housing 304 interiorly of the housing 14. A gear 306 is fixed to the upper end of the shaft 296 for meshing with suitable driving means to effect rotation of the carrier 294, and a nut 308 threaded onto the upper end of the shaft 296 may be tightened to prevent play of said shaft in an axial direction.

A fabricated funnel ring indicated generally at 310 is concentrically secured to the upper surface of the carrier 294. The ring 310, in the particular embodiment shown, is made up of a plurality of individually formed sheet metal funnel members 310a secured in side-by-side relation about the upper marginal edge of the carrier 294, as best shown in Figs. 1 and 2. Each of the funnel members 310a is adapted to be moved in turn by the carrier 294 into position below the discharge opening in the hopper 292. Immediately below each funnel member 310a on the carrier 294, a carton-holding member 311 is positioned. The carton-holding members 311, as best shown in Figs. 5 and 8, each consist of a box-like structure formed from sheet metal. The side walls are spaced from one another by a distance slightly greater than the width of the cartons 312 which are to be received therein and the top wall is provided with a central opening which matches the discharge opening in the overlying funnel member 310a. The rear wall of each carton-holding member is so located that when a carton 312 is properly positioned therein the carton will be centered with respect to the discharge opening of the corresponding funnel member. The front wall of each member 311 is bent outwardly as at 313 about its upper edge into flush relationship with respect to the top wall thereof, leaving the front of each member 311 open to receive a carton 312 therein. The cartons 312 preferably are of a conventional type having short top flaps 314 along each side and a long front flap serving as a cover shown at 315 by dotted lines in Fig. 5. In inserting a carton into a member 311 the side flaps 314 are turned outwardly 270°, as indicated in Fig. 8, and the front flap turned outwardly 180° as indicated in Fig. 5, and then inserted in the member 311, which thus holds the flaps in this position with the top of the carton open to receive the clips delivered thereto by the corresponding funnel member 310a.

Movement of the carrier 294 is intermittent and timed to rotate a carton into position as soon as the preceding carton has been filled with a proper number of clips.

To effect driving of the apparatus of the present invention, a prime mover in the form of an electric motor 318 is preferably provided, as shown in Fig. 2. The motor 318 may be mounted on the floor of the shop on the base, or be otherwise suitably positioned, so as to drive a pulley 320. By means of an endless belt 322, a second pulley 324 is driven from pulley 320. The pulley 324, which, as best shown in Fig. 3, is fixed to the outer end of a main drive shaft 326, drives such shaft. The shaft 326 is journaled for rota-

tion within a sleeve 328 and bearings 330 and 331 both of which are suitably carried by and retained in a housing 332 within the housing 14 of the machine. A beveled pinion 334 is fixed to the inner end of the shaft 326 and meshes with the gear 143 to drive shaft 126 for rotating the carriage 122.

The wire feeding means 26 is driven in timed relation with the rotation of the carriage 122, and although this drive may include intermittent drive mechanism to stop the feed of wire at the moment it is cut, because the wire is cut almost instantaneously this will usually be unnecessary and is so considered here. Accordingly, the beveled gear 142 on the shaft 126 meshes at each of the wire feeding stations with a pinion 336, as may be seen in Fig. 3, driving a shaft 338. Each shaft is journaled for rotation within a sleeve 340 having bearings 342 and 343 therefor and retained within a housing 344 positioned interiorly of the housing 14. A bevel gear 346 is fixed to the outer end of shaft 338, which is at the right as viewed in Fig. 3, and referring to Fig. 4 it may be seen that the beveled gear 346 meshes with a beveled gear 348 to drive a shaft 350 journaled for rotation on bearings 352 and 354. The shaft 350 in turn drives shaft 44 by means of a train of gears 352, 354, 356, and 358 to drive the outermost feed roller 54.

Driving of the innermost feed roller 54 is accomplished by means of another beveled gear 360 mounted on the shaft 338 and shown in Fig. 3. The beveled gear 360 drives a beveled gear 362 mounted on a shaft (not shown) which drives a train of gears 364, 366, 368, and another gear (not shown) to drive shaft 50 for driving the innermost feed roller, in the same general manner as the roller 54 is driven.

Rotation of the tumbler 88 and thereby the wire straightening means is effected by a gear 370 (see Fig. 3) fixed to the shaft 338 and spaced thereon a short distance inwardly from the gear 346. The gear 370 meshes with a gear 372 mounted on a jack shaft 374 which meshes with a gear 376 keyed to shaft 90 of the tumbler 88.

In Fig. 5, the driving connection between the main drive shaft 326 and the carrier 294 is illustrated. This includes an intermittent motion mechanism which may be of any suitable type, the type shown being illustrative of a satisfactory type. As shown in Fig. 5, a worm 378 is keyed to the shaft 326 for driving a worm wheel 380 fixed to shaft 382. A gear 384 is also keyed to the shaft 382 and this gear meshes with a gear 386 for driving a shaft 388 and thereby moving an arm 390 thereon in rotation.

The arm 390 provides a means in a manner to be next described for effecting intermittent rotation of the carrier 294. A roller 392 is rotatably mounted by means of a journal pin 394 on the extremity of arm 390. As the arm 390 rotates, the roller 392 thereon engages one of a plurality of radially extending equally angularly spaced ribs 396 upstanding from the upper face of a disc 398. The disc 398 is provided with an integral shaft 400 and as the roller 392 rolls along the surface of a co-operating rib 396, rotation of the disc 398 and thereby shaft 400 is brought about so long as roller 392 remains in engagement with the rib surface. Thereafter, rotation of the shaft 400 ceases until contact is again established between the roller 392 and a succeeding rib 396. When the shaft 400 is driven in this manner, a gear 402 fixed thereto drives the carrier 294 by means of inter-

related gearing and shafting 404, 406, 408, 410, 412, and 306.

From the foregoing, it will be understood that at each of the stations 26 wire from the coil is withdrawn from the coil, first straightened, and then fed into the corresponding groove 118 on the underside of the stationary head 116 where it is held until a proper length has been fed, whereupon a cutter blade 186 severs such length which is simultaneously picked up by the plungers 148, 150 and 152 on the rotating carriage 122 and caused to rotate with the rotating carriage. It will be further understood that as such rotation of the carriage progresses the outer end portion of the wire carried thereby is first initially bent by engagement with the striker 202 and then the bend completed through engagement with the die 203, upon which the plunger 148 is retracted to remove the projection 180 thereof out of engagement with the wire. Further, that during further rotation of the carriage 122 the outer and initially bent end of the wire is then brought into engagement with the striker 246 and then into contact with the die 248 to again bend the wire to produce and complete the second bend therein, upon which the plunger 150 is withdrawn to withdraw the projection 181 thereof out of engaging relation with respect to the wire. It will be further understood that upon further rotation of the carriage 122, the outer and thus doubly bent end of the wire is next brought against the stationary striker 260 and then into engagement with the die 262 to complete the final and third bending of the wire, whereupon the plunger 152 is withdrawn to free the projection 182 thereof from the wire and to release the wire from clamping relationship with respect to the carriage 122, thereby to discharge the completed clip into the hopper mechanism and cartons there awaiting it.

It will be appreciated that in so forming a wire into a paper clip of the type described, the bending operations on the wire are accomplished during a continued steady rotation of the carriage 122 and that the only reciprocable parts required are the plungers 148, 150, and 152 which are carried by and continuously moved with the carriage 122 and which are required to be reciprocated through a distance equal only to substantially the thickness of the wire, which small distance results in a minimum of inertia and other forces required to be overcome in the reciprocation of the plungers with a consequent minimum resulting wear and tear on the machine. As a result, it will be appreciated that the machine may be operated at a relatively high speed with a minimum of wear on the co-operating parts, resulting in important economies in production.

Furthermore, those parts of the machine which are most subject to wear are the fixed strikers 202, 246, and 260 and corresponding dies 203, 248 and 262, respectively, each pair of which are mounted in a readily removable and replaceable unit, namely, the units 199, 200, and 201, which may be removed and replaced in a minimum amount of time and with a minimum amount of effort, thus cutting down the idle time required to replace these parts when they become worn and require replacement. This feature leads to further economies in production as the relative percentage of running time is therefore increased. Other features specifically shown and described do, of course, add to the advantages above described, but may be considered more or less subordinate to the major features above identified.

There may be some instances where ejection of

a finished clip from the machine under centrifugal force may be resisted, as for instance, by burrs on the clip engaging the holding member 170, or where, for some other reason, the clips may fail to readily free themselves from the holding member 170. In such case, resort may be had to the construction illustrated in Figures 32 to 35, inclusive, wherein the inner end of the wire, which is fed into the machine and held until the final bending operations are completed, is held between a pair of oppositely movable plungers which, when the forming operation is completed, simultaneously withdraw away from the clip so as to positively and completely free the clip for ejection under centrifugal force.

Referring to Figures 32 to 35, inclusive, it will be noted that the holding member 170 has been eliminated and a member 420 has been substituted therefor. The member 420, as brought out in Figure 34, is somewhat thicker in its vertical dimension than the member 170 but, like the member 170, is rigidly fixed to the upper face of the carriage 122 in partially overlying relationship with respect to the plunger 152. The head plate 16 in this case is vertically recessed as at 422 to a greater extent than in the first described construction not only to provide clearance for the movement of the member 420 therein, but also to provide space for a cam member 424 above the member 420. The cam member 424 is of a partially annular conformation and fits in and against the upper wall of the groove 422, where it is fixedly secured by means of screws 426.

The member 420, as best brought out in Figure 32, is provided with a vertical T-sectioned slot 428 therein, which opens onto its radially outer face immediately above the plunger 152. Vertically reciprocally received within the slot 428 is a complementarily shaped, vertically movable holding member or plunger 430. The upper end of the holding member 430 is diametrically slotted and received within the slot is a roller 432 rotatably mounted on a pin 434 bridging the opposite sides of the slot. The holding member 430 is constantly urged upwardly by means of a pair of coil tension springs 436 tensioned between a pair of inwardly projecting pins 438 carried by the member 420 and a transversely projecting pin 440 in the member 430, the springs 436 being received in pockets 442 formed in opposite walls of the slot 428. The lower end of the holding member 430, on its leading side in the direction of rotation of the carriage 22, as best shown in Figure 33, is provided with a downwardly projecting part 434 arranged in parallel relation with respect to the blade 178 in the plunger 152, and corresponds to the nose portion of the holding member 170 of the first described construction.

From the foregoing, it will be appreciated that the holding member 430 is normally urged to an upper inoperative position. The cam member 424 is so constructed that at about the time the wire 30 is fully threaded into the groove 118 in the head plate 116, a "rise" or downward projection 65 on cam 424 moves the holding member 430 downwardly. At such time, the holding member 430 overlies the inner end of the wire in the groove 118 and thus moves the inner end of the wire downwardly in the same manner as the tapered nose 174 of the holding member 170 operates in the first described construction. It will, of course, be appreciated that at this time the plunger 152 is being raised simultaneously therewith so that the two plungers (for the holding member 430 is, 70 in effect, a plunger) 430 and 152 move toward

each other so as to clamp the inner end of the wire 30 between them below the head plate 16. Such inner end of the wire is positioned against the upstream side of the blade 178, in the same manner as in the first described construction, and the downward projection 444 of the holding member 430 is shaped to maintain it in this position. The bending operations described in connection with the first described construction proceed until the clip is fully completed, whereupon the holding member 430 reaches a drop in the cam 424 and rises while plunger 152 simultaneously descends, thus completely freeing the inner end of the thus formed clip and eliminating any possibility of any resistance being set up, for the reasons before stated, which might interfere with its free outward movement or ejection under the centrifugal force of the head 122 in rotating. Otherwise, the construction is identical to that in the first described construction.

Formal changes may be made in the specific embodiment of the invention described without departing from the spirit or substance of the broad invention, the scope of which is commensurate with the appended claims.

Having thus described my invention, I claim:

1. The method of forming a wire paper clip comprising the steps of continuously bodily moving a length of wire sideways along a predetermined path and in one direction, and forming in succession a plurality of U-shaped bends in said wire at different points along the length thereof.

2. The method of forming a wire paper clip comprising continuously moving a length of wire bodily sideways along a predetermined path in one direction, rigidly anchoring one end of said wire against displacement from said movement, first bending said wire about an axis adjacent the end thereof more remote from said clamped end through an angle of approximately 180°, then bending said wire about an axis intermediate the first-mentioned axis and said clamped end thereof through an angle of approximately 180° and on a slightly larger radius than the first-mentioned bend, and then bending said wire about another axis positioned adjacent said clamped end through about 180° and on a radius slightly greater than the last-mentioned radius, and then freeing said anchored end.

3. The method of forming wire paper clips comprising bodily moving a length of wire sideways along a predetermined path, backing up said wire at spaced points in the length thereof against retrograde movement, first bending said wire through approximately 180° at that one of said backing up points closest to one end of said wire and then rendering the backing up effect at said point inoperative for backing up purposes, then bending said wire through approximately 180° at the next backing up point and then rendering the backing up effect at such point inoperative, then again bending said wire through approximately 180° at the next backing up point and then rendering the backing up effect at the last-mentioned point inoperative.

4. The method of making a wire paper clip from a length of wire comprising moving said length of wire sideways along a predetermined path, backing said wire up against retrograde movement at spaced points in the length thereof, and then consecutively bending said wire through approximately 180° at each of said backing up points from one end of said wire toward the other end thereof and rendering the backing up effect

at said points inoperative upon the completion of a bending operation thereat.

5. Paper clip forming mechanism comprising, in combination, a carriage and a head movable in one direction with respect to each other, means for delivering a length of wire to said carriage with the length of the wire disposed substantially transversely to the direction of said relative movement, means for releasably clamping an end of said wire to said carriage, retractile abutment means on said carriage arranged in backing up relation with respect to said wire at points spaced in the length thereof, and forming means on said head positioned in the path of relative movement of said wire with respect to said head cooperable with said abutment means to consecutively engage and bend said wire at said points, first adjacent that end of said wire more remote from said clamping means, and means for releasing said clamping means upon completion of said bending operations.

6. In a paper clip forming machine, in combination, a carriage member and a head member continuously relatively movable with respect to each other in one direction, means for applying a length of wire to one of said members with its length disposed substantially transversely of the direction of relative movement between said members, means for clamping one end of said length of wire to said one of said members, retractile abutment means carried by said one of said members in backing up relation with respect to said length of wire in the direction of movement between said members and in spaced relation with respect to each other away from said clamping means, a plurality of forming means carried by the other of said members, said forming means being spaced from each other in the direction of relative movement between said members and each cooperable with one of said abutment means to bend said wire as said abutment means and forming means successively pass each other during said relative movement between said members, and means for releasing said clip from said one of said members upon completion of said bending operations on said length of wire.

7. A paper clip forming mechanism comprising, in combination, a pair of members continuously relatively movable with respect to each other in one direction, means for applying a length of wire to one of said members with the length of the wire positioned to move sideways along a predetermined path with said member, plunger means reciprocably mounted in said one of said members for movement in a direction transverse to the plane of relative movement of said wire with respect to the other of said members, said plungers being spaced from one another over the length of said wire and formed to engage and hold said wire when reciprocated into contact therewith, means to effect reciprocation of said plungers substantially simultaneously with each other toward operative position and for retracting said plungers consecutively from one end of said wire towards the other end thereof, and forming means carried by said other of said members in a position to engage said wire during relative movement between said members, said forming means being arranged to consecutively engage said wire at different points in the length thereof during relative movement between said members and each cooperating with one of said abutments to bend said wire about such abutments, said plungers reciprocating means being arranged to withdraw each said plunger and its abutment upon the com-

pletion of the bending operation thereabout.

8. Paper clip forming mechanism comprising, in combination, a rotatable carriage, a stationary head, means for continuously driving said carriage in one direction of rotation, means for feeding a piece of wire to said carriage in approximately radial relation with respect to the axis of rotation thereof, a plurality of plungers carried by said carriage and arranged with their axes approximately parallel to the axis of rotation of the said carriage and in spaced relation to each other radially of said carriage, means for reciprocating said plungers during rotation of said carriage, an abutment on an end of each of said plungers adapted to be reciprocated into backing up relation with respect to said wire on said carriage and the plunger adjacent one end of said wire serving to releasably clamp said end of said wire to said carriage for bodily movement therewith, forming means carried by said head and projecting into the path of movement of said wire on said carriage during relative movement between said head and said carriage, said forming means being arranged to consecutively engage and in conjunction with said abutments bend said wire during said rotation at points in the length of said wire corresponding with said abutments, said plunger actuating means serving to withdraw each said plunger and its corresponding abutment from engagement with said wire upon bending of said wire about the corresponding abutment thereof.

9. Paper clip forming mechanism comprising, in combination, a rotatable carriage, a stationary head, means for continuously driving said carriage in one direction of rotation, means for feeding a piece of wire to said carriage in approximately radial relation with respect to the axis of rotation thereof, a plurality of plungers carried by said carriage and arranged with their axes approximately parallel to the axis of rotation of the said carriage and in spaced relation to each other radially of said carriage, means for reciprocating said plungers during rotation of said carriage, an abutment on an end of each of said plungers adapted to be reciprocated into backing up relation with respect to said wire on said carriage and the plunger adjacent one end of said wire serving to releasably clamp said end of said wire to said carriage for bodily movement therewith, forming means carried by said head and projecting into the path of movement of said wire on said carriage during relative movement between said head and said carriage, said forming means being present in units corresponding in number to the number of said plungers and each including a stationary striker member and a rotatable coining member, said forming means being arranged to consecutively engage and in conjunction with said abutments bend said wire during said rotation at points in the length of said wire corresponding with said abutments, said plunger actuating means serving to withdraw each said plunger and its corresponding abutment from engagement with said wire upon bending of said wire about the corresponding abutment thereof.

10. In a paper clip fabricating machine, in combination, a stationary head plate, a rotatable carriage in relatively close axial relationship with respect thereto, said head plate having means on that face thereof opposed to said carriage and generally centrally directed with respect to the axis of said carriage for receiving a piece of wire, means for feeding wire to the first-mentioned means, means for severing a piece of wire of pre-

determined length received in said first-mentioned means, means operable to transfer said severed length of wire from said first-mentioned means to said carriage for rotation therewith, means carried by said head successively engageable with said severed length of wire as it rotates with said carriage, and means carried by said carriage co-operating with said last-mentioned means operable to bend said wire at successively different points in the length thereof and then release said bent wire from said carriage.

11. In a paper clip fabricating machine, in combination, a stationary head plate, a rotatable carriage in relatively close axial relationship with respect thereto, said head plate having means on that face thereof opposed to said carriage and generally centrally directed with respect to the axis of said carriage for receiving a piece of wire, means for feeding wire to the first-mentioned means, means for severing a piece of wire of predetermined length received in said first-mentioned means, means operable to transfer said severed length of wire from said first-mentioned means to said carriage for rotation therewith, means carried by said head successively engageable with said severed length of wire as it rotates with said carriage, and means carried by said carriage co-operating with said last-mentioned means operable to bend said wire at successively different points in the length thereof and then release said bent wire from said carriage, including plunger means movable in a direction transverse to the general plane of the opposed faces of said head and carriage.

12. A paper clip fabricating machine including, in combination, a stationary head plate, having a groove therein, means for feeding wire into said groove in said head plate, means to drive said feeding mechanism, forming means in said head plate, a rotatable carriage in relatively close axial relationship with respect to said head plate, means to rotate said carriage in synchronism with said wire-feeding means, means operatively associated with said carriage for moving the wire from said groove in said head plate onto said carriage for delivery thereby into engagement with said forming means, and means for severing a length of wire as the same is removed from said groove.

13. A paper clip fabricating machine, including, in combination, a stationary head plate having a groove therein, means for feeding wire into said groove in said head plate, means to drive said feeding mechanism, a rotatable carriage in relatively close axial relationship to said head plate, means to rotate said carriage in synchronism with said feeding means, forming means including striker members and die members in the face of said head plate in opposed relation to said carriage, means on said carriage for initially moving the innermost end of said wire from said groove onto said carriage, means operatively associated with said carriage for clamping said innermost wire end as it moves onto said carriage and thereafter moving the remainder of said wire from said groove onto said carriage for delivery thereby into engagement with said forming means, and means for severing a length of wire as the same is removed from said head slot.

14. A paper clip fabricating machine including, in combination, a base, a stationary head plate, having a groove therein, means for feeding wire into said groove in said head plate, means to drive said feeding mechanism, forming means

including a plurality of striker members and die members arranged in consecutive units of a die member and a striker member depending from said head plate, a carriage rotatably mounted on the base and axially spaced from said head plate, means to rotate said carriage in synchronism with said feeding means, means having a sloping leading edge mounted on said carriage to contact the innermost end of said wire in said slot for moving it along said leading edge onto said carriage, reciprocable means in said carriage for clampingly engaging said innermost wire end as it moves onto said carriage and thereafter moving the remainder of said wire from said groove onto said carriage for delivery thereby into contact with said forming means, and means in the periphery of said carriage for severing a length of wire as the same is moved onto said carriage.

15. A paper clip fabricating machine including, in combination, a stationary head plate, having a groove therein, means for feeding wire into said groove in said head plate, means to drive said feeding mechanism, forming means including a plurality of striker members and a plurality of rotatable die members positioned in consecutive sets of a striker member and a die member depending from said head plate, a carriage rotatably mounted below the head plate and axially spaced therefrom, means to rotate said carriage in synchronism with said feeding means, a holding element having a sloping leading edge mounted on said carriage to contact the innermost end of said wire and move it along said leading edge onto said carriage, a plurality of reciprocable plungers in said carriage, means for moving one of said plungers into clamping engagement with said innermost wire end as it moves onto said carriage and means for moving the other plungers to engage the remainder of said wire in said groove for moving it onto said carriage whereby to move said wire in rotation into engagement with said forming means, said plunger moving means dropping said plungers singly to inoperative position as the forming means are passed, and means in the periphery of said carriage for severing a length of wire as the same is removed from said head slot.

16. A paper clip fabricating machine including, in combination, a base, a stationary head plate having a groove therein with one of the walls thereof sloped to provide a groove wider at its opening side than at its bottom, mechanism for feeding wire into said groove in said head plate, means to drive said mechanism, forming means including striker members and rotatable die members positioned in successive sets of a striker and a die depending from the head plate, a carriage rotatably mounted below the head plate and axially spaced therefrom, means to rotate said carriage in timed relation to said wire feeding means, a holding element having a sloping leading edge mounted on said carriage to contact the innermost end of said wire and move it along said leading edge onto said carriage, a plurality of reciprocable plungers in said carriage, means for moving one of said plungers into clamping engagement with said innermost wire end as it moves onto said carriage and means for moving the other plungers to engage the remainder of said wire in said groove for moving it onto said carriage for movement in rotation therewith into successive engagement with said forming means, said moving means thereafter dropping said plungers to inoperative position, means for severing a length of wire

as the same is moved onto said carriage, rotatable means in one end of each plunger, said moving means comprising cam tracks in said base for raising the plungers to operative position as said carriage rotates, and resilient means in said carriage tending to maintain said plungers in contact with said cam tracks thereby to move plungers to inoperative position during certain rotatable positions of said carriage.

17. A paper clip fabricating machine including, in combination, a base, a stationary head plate having a groove therein, one wall of which is sloped to provide a groove increasing in width from the bottom, means on said base for feeding wire into said groove in said head plate, a carriage rotatably mounted below the head plate and spaced axially therefrom, means for driving said mechanism and rotating said carriage, a holding element having a sloping leading edge mounted on said carriage for engaging the inner end of the wire when the same is fed fully into said groove in the head plate and moving the wire downwardly along said leading edge as the carriage rotates, a plunger having a grooved upper surface mounted in the carriage and reciprocable into operative position co-operating with said holding element for clampingly engaging said inner end of the wire and holding the same at the level of the upper surface of said carriage when the same is brought into the groove in said plunger, a wire cutter in the periphery of the carriage for cutting off a length of wire after said inner end is clamped, other plungers having grooved upper surfaces mounted in the carriage and reciprocable between operative and inoperative positions, means on said other plungers operable when said other plungers are in operative position to engage the free end of said cut-off length of wire and move the same downwardly along said slanted wall of said groove in said head plate into the grooves in the tops of said other plungers at the level of the upper surface of said carriage as the same rotates, rollers on the bottom of each plunger to move the same into operative positions, annular cam tracks in the base each operatively associated with a respective plunger roller, a plurality of forming means including strikers and rotatable dies arranged in successive sets of a striker and a die depending from the head plate in the vicinity of said groove therein to successively bend and form the wire as the same is delivered thereto by the rotating carriage, and resilient means in the carriage for singly moving the plungers to inoperative positions after the wire passes each set of forming means.

18. A paper clip fabricating machine including, in combination, a base, a head plate having a groove therein, means to feed wire into said groove, means to cut off a length of wire after the same is fed into said groove, a plurality of forming units mounted in the head plate, each comprising a mounting member, a striker member, and a rotatable die, and rotatable means for removing said cut-off length of wire from said groove and delivering the same to said forming means.

19. A paper clip fabricating machine including, in combination, a base, a head plate having a groove therein, means on the base for feeding wire into said head groove, said means comprising means for rotatably supporting a roll of wire, spaced feeding rollers for said wire, means to press the wire against the periphery of said feeding rollers, a tumbler mounted between said pressure rollers, a plurality of plunger in each end

of the tumbler, and rollers on each plunger to operatively engage the wire as the same moves through said tumbler; means to drive the first mentioned means, means to cut off a length of wire after the same is fed into said groove, a plurality of forming units mounted in the head plate in the vicinity of said slot, each unit including a striker member, and a die; and rotatable means for removing said cut-off length of wire from said groove and delivering the same to said forming means.

20. A paper clip fabricating machine including, in combination, a base, a stationary head plate thereon having a groove therein with one of the groove-defining walls being sloped to provide a slot increasing in width from the bottom, means on said base for feeding wire into said groove in said head, a rotatable carriage in relatively close axial relationship with respect to said head plate, means to drive the first-mentioned means and to rotate said carriage, a holding element having a sloping leading edge mounted on said carriage for engaging the inner end of the wire when the same is fed fully into said groove in the head and moving the wire downwardly along said leading edge to said carriage as the carriage rotates, a plunger having a grooved upper surface mounted in the carriage and reciprocable into operative position co-operating with said holding element for clampingly engaging said inner end of the wire when the same is brought into the groove in said plunger, means for severing a length of said wire substantially at the time said inner end is clamped, other plungers having grooved upper surfaces with wire-engaging elements thereon mounted in the carriage and reciprocable into operative position for engaging the free end of said cut-off length of wire and moving the same downwardly along said sloped wall in said head into the grooves in said plungers, annular cam tracks carried by said base each operatively associated with a respective plunger, a plurality of sets of forming means in said head plate to successively engage said severed length of wire as said carriage rotates for successively bending and forming the wire, resilient means in the carriage for singly moving the plungers to inoperative positions after the wire passes each set of forming means, and means operable upon failure of said resilient means to retract said plungers in said carriage.

21. A paper clip fabricating machine including, in combination, a base, a head plate thereon having a groove therein with one of the groove-defining walls sloped to provide a groove increasing in width from the bottom, means on said base for feeding wire into said groove, a carriage rotatably mounted below the head plate and spaced axially therefrom, means to drive the first-mentioned means and to rotate said carriage, a holding element mounted on said carriage, a sloping leading edge on said holding element for engaging the inner end of the wire in said groove and moving the same downwardly onto said carriage as said carriage rotates, a plunger slidably mounted in the carriage and having a grooved upper surface movable with said plunger to operative position to co-operate with said holding element for clampingly engaging said inner end of the wire, a cutter in the periphery of the carriage for severing a length of wire at about the time said inner end is clamped, other plungers slidably mounted in said carriage for movement into operative positions and having grooved upper surfaces with wire-engaging elements thereon for engaging the free end of said severed wire

and moving the same downwardly along said sloped wall in said head into said plunger grooves as said carriage rotates, annular cam tracks in the base, rollers on the bottom of each plunger each operatively associated with a respective car track to move a respective plunger into operative position, a plurality of forming means arranged in successive sets of a striker and die depending from the head plate to successively bend and form the wire about the wire engaging elements of said plungers as the same is delivered thereto by said rotating carriage, resilient means in the carriage for singly moving the plungers to inoperative positions after the wire passes each set of forming means, a second roller on each plunger, and cam means positioned adjacent said cam tracks to operatively engage said second rollers upon failure of said resilient means to forcefully retract said plungers.

22. Paper clip forming mechanism comprising, in combination, a rotatable carriage, a stationary head, means for continuously driving said carriage in one direction of rotation, means for feeding a piece of wire to said carriage in approximately radial relation with respect to the axis of rotation thereof, a plurality of plungers carried by said carriage and arranged with their axes approximately parallel to the axis of rotation of the said carriage and in spaced relation to each other radially of said carriage, means for reciprocating said plungers during rotation of said carriage, an abutment on an end of each of said plungers adapted to be reciprocated into backing up relation with respect to said wire on said carriage and the plunger adjacent one end of said wire serving to releasably clamp said end of said wire to said carriage for bodily movement therewith, forming means carried by said head and projecting into the path of movement of said wire on said carriage during relative movement between said head and said carriage, said forming means being so arranged to consecutively engage and in conjunction with said abutments bend said wire during said rotation at points in the length of said wire corresponding with said abutments, an additional plunger arranged in axially opposed relation to that one of the first mentioned plungers whose abutment is last withdrawn from engagement with said wire and co-operating with said one of said plungers to clamp the corresponding portion of said wire therebetween, means for moving said additional plunger axially in timed relation with and oppositely to said one of said plungers, said plunger actuating means and the last mentioned means serving to withdraw each said plunger and its corresponding abutment from engagement with said wire upon bending of said wire about the corresponding abutment thereof, and said additional plunger simultaneously with said one of said plungers.
